UNITED STATES PATENT OFFICE

FLOYD E. WHITE, OF WINAMAC, INDIANA

ELECTRIC CLOCK

Application filed December 8, 1928. Serial No. 324,771.

This invention relates to electric clocks, and more particularly to a clock for electrically signalling a selected time.

An important object of the invention is to provide an apparatus of this character which may be very readily adjusted to enable the transmission of electric signals and to provide for such signals at a plurality of points and upon different circuits, if so desired.

10 A still further object of the invention is to provide a device of this character which may be very cheaply produced and very readily installed, and which is especially adapted for use in schools and the like for signalling class hours.

These and other objects I attain by the construction shown in the accompanying drawing, wherein for the purpose of illustration is shown a preferred embodiment of my invention and wherein:

Figure 1 is a front elevation partially broken away of clock mechanism constructed in accordance with my invention;

Figure 2 is a fragmentary transverse sectional view therethrough;

Figure 3 is a detail sectional view showing the stationary element of the switch;

Figure 4 is a similar view showing a modified form of the stationary element.

30 Referring now more particularly to the drawing, the numeral 10 generally designates a case containing the clockworks which may be of the type usually employed in alarm clocks. To the hour hand staff or shaft 11, I

35 secure a sleeve 12 similar to the sleeve usually employed in connecting the hour hand thereto. This sleeve has radiating therefrom a plurality of arms 13, the outer ends of which are rigidly secured to an annulus 14 which

40 preferably has an internal diameter slightly greater than the clock case. The arms 13 are slightly offset, so that this disk surrounds the clock case at the approximate center thereof. The periphery of this disk is provided with

45 spaced hour indicia 15 and associated with each indicia 15 is a means for attaching to the disk a wire 16. Such means are likewise provided at quarter and half hour intervals, as indicated, or in small intervals if desired and in the present instance are disclosed

as openings 17 formed in the disk and adapted to receive one end of the wire. The wire employed is angular, so that its free end portion may project in a plane paralleling the disk and extend beyond the rim thereof. 55

With this mechanism, I provide a suitable base 18 from which, by adjusting screws 19 and 20, I support a slightly concave insulating plate 21, the concavity of the plate extending in the general direction of curvature 60 of the edge of the annulus 14.

At the center of this plate, a groove 22 is formed and a lead wire 23 is extended from the bottom of this groove through the disk. The adjusting screws 19 permit alignment 65

of this groove with a desired portion of the periphery of the annulus in such manner that the projecting portions of the wires 16 will pass through a drop of mercury 24 positioned in the groove to establish electrical connection between the lead wire 23 and the annulus. If desired, the wires 16 may be multi-pronged, as indicated in Figure 4, and the base may be provided with a plurality of 70

grooves 22 for the reception of mercury drops 24 for coaction with these prongs. Similarly, the prongs may be variously offset from the face of the annulus and by providing a plurality of grooves 22 and mercury drops 24, signals may be given at different times upon different circuits. To complete the signal circuit, a source of current 75

B may be connected through the signal S with the frame 10 of the clock, a switch 25 being preferably provided in the circuit to 80 enable the same to be rendered inoperative at any time.

It will be obvious that with a construction of this character, a very cheap time-controlled electrical signal may be provided which will be reasonably accurate and which may be readily adjusted to correspond to any change in the signalling time. It will also be obvious that the construction employed is capable of a certain range of change and modification without materially departing from the spirit of the invention and I accordingly do not limit myself thereto except as hereinafter claimed. 95

I claim:

1. In combination, a member having a circular periphery having time indicia thereon, a clockworks for rotating the member, a relatively stationary member having a socket formed therein, a conductor extended into said socket, a liquid conductor disposed in the socket and of a character such that it projects above the surface of the member, and an angularly inclined rigid conductor adjustably connectible with the periphery of the rotating member.

2. In combination, a member having a circular periphery having time indicia thereon, a clockworks for rotating the member, a relatively stationary member having a socket formed therein, a conductor extended into said socket, a liquid conductor disposed in the socket and of a character such that it projects above the surface of the member, and an angularly inclined rigid conductor adjustably connectible with the periphery of the rotating member, the relatively stationary member being adjustable circumferentially of and toward and away from the first named member.

3. In combination, a member having a circular periphery having time indicia thereon, a clockworks for rotating the member, a relatively stationary member having a socket formed therein, a conductor extended into said socket, a liquid conductor disposed in the socket and of a character such that it projects above the surface of the member, and an angularly inclined rigid conductor adjustably connectible with the periphery of the rotating member, said rotating member having spaced openings in its periphery, the conductor carried thereby being angular in form and having an end portion adapted for selective engagement in said openings.

4. In combination, a member having a circular periphery having time indicia thereon, clockwork means for rotating the member, a relatively stationary member having a plurality of sockets formed therein, a conductor extending into each socket, a mercury contact in each socket, and angularly inclined rigid conductors adjustably connectible with the periphery of the rotating member having terminal portions for engagement with the mercury contacts of said sockets as the rotatable member is rotated.

5. In combination, a member having a circular periphery having time indicia thereon, clockwork means for rotating the member, a relatively stationary member having a plurality of sockets formed therein, a conductor extending into each socket, a mercury contact in each socket, and angularly inclined rigid conductors adjustably connectible with the periphery of the rotating member having terminal portions for engagement with the mercury contacts of said sockets as the rotatable member is rotated, said relatively stationary member being adjustable toward and

away from and circumferentially of the rotatable member.

6. In combination, a member having a circular periphery having time indicia thereon, a clockworks for rotating the member, a relatively stationary member having sockets formed therein, a conductor extended into each socket, a liquid conductor disposed in the socket and of a character such that it projects above the surface of the member, and a rigid conductor adjustably connectible with the periphery of the rotating member, said rotating member having spaced openings in its periphery, the conductor carried having a plurality of depending conductor engaging members having an end portion adapted for selective engagement in said openings, the relatively stationary member being adjustable circumferentially of and toward and away from the first named member.

In testimony whereof I hereunto affix my signature.

FLOYD E. WHITE.
